ATTORNEY

UNITED STATES PATENT OFFICE.

EDWARD E. ROSE, OF SWISSVALE, PENNSYLVANIA, ASSIGNOR TO WESTINGHOUSE ELECTRIC & MANUFACTURING COMPANY, A CORPORATION OF PENNSYLVANIA.

INSULATOR CONNECTER.

Application filed September 13, 1919. Serial No. 323,607.

To all whom it may concern:

Be it known that I, EDWARD E. Rose, a citizen of the United States, and a resident of Swissvale, in the county of Allegheny and State of Pennsylvania, have invented a new and useful Improvement in Insulator Connecters, of which the following is a specification.

My invention relates to connecters and particularly to connecters employed in connecting series-related insulator sets.

One object of my invention is to provide a device of the above indicated character that shall facilitate the connection and disconnection of the members of a series insulator set and reduce the overall length of the insulator set to substantially a minimum.

Another object of my invention is to provide a yieldable connecting member or loop that shall comprise longitudinally co-operating complementary portions that together constitute a member of substantially circular cross-sectional area to better seat itself with respect to an insulator and permit the ends thereof to be securely wedged and swaged in connection with a co-operating connecting member.

In the prior art, difficulty has been experienced in providing an effective and convenient connecter, for insulators of the so-called disc type, that, at the same time, did not occupy excessive space between the insulating members. Also, in connection with all out-door installations which support high-potential conductors and are usually of elevated open construction, thereby constituting great hazards for the linemen, it is particularly desirable that all installation and renewal operations shall be facilitated to a maximum degree. This is particularly true during wet or cold weather, when the manipulation of all small parts, such as nuts, screws, etc., becomes an exceedingly difficult and tedious operation.

In practicing my invention, I provide a connecter comprising relatively-narrow complementary connecting members that extend transversely with respect to the insulator members, thereby permitting the latter to be placed close together and reducing the overall length of a series thereof. A simple transversely-operable pin or wedge facilitates the connection and disconnection of the complementary members.

In place of the ordinarily looped cable or U-bolt for interlinking the insulators, I provide a member of substantially circular cross-sectional area and comprising longitudinal complementary half members. These members, preferably of malleable material, extend through tapered openings in the above-mentioned complementary members, wherein wedges separate them and are held in position by the ends of the half members that are swaged laterally over the ends of the wedges.

Figure 1 of the accompanying drawings is a side view, partially in elevation and partially in section, of an insulator and connecters embodying my invention; Fig. 2 is a plan view of an assembled connecter and Fig. 3 is a detail view of one of the complementary connecting members embodied in my invention.

Insulating members 1, preferably of porcelain and of the disc type, are provided with angularly-related transverse curved openings 2 for the reception of interlinked, preferably yieldable, metal members 3 having ends 4 projecting oppositely from the members 1.

The members 3 comprise complementary half-round or semi-circular cable or connecter portions 5, the outer ends 4 of which extend through tapered openings 6 in transverse metal members 7 and have swaged portions 8 projecting over the ends of metal wedges 9. This construction provides a member that conforms to the insulator, in a manner similar to that of a flexible round cable, thereby adjusting itself to irregularities, and evenly distributing the stresses in the porcelain and, by reason of its simplicity and the small number of its parts, provides a more convenient and durable connection to the member 7 than is usually effected with a multistranded cable or threaded rod.

The members 7, which are identical and interchangeable, are of substantially yoke-shape having relatively flat transverse mid portions 10, hubs 11 having the openings 6 extending in the direction of the axis of the insulator and co-operating transversely-apertured lugs 12 and 13, also extending in the direction of the insulator. Each member 7 is provided with two of the lugs 12 closely related at one end thereof for the re-

ception of the lug 13 of the other member 7 and one lug 18, at its other end, to interfit between the lugs 12 of the other member 7.

The openings in the lugs 12 and 13 are adapted for the reception of, and to conform to, a preferably tapered member or pin 14 that may be wedgingly maintained in operative position or be bent or otherwise secured after its insertion.

10 The assembly of the members 1, 3 and 7
is preferably a bench operation, effected at
the factory, whereby a plurality of readily-
transportable and conveniently-mountable
insulator units are constructed which may
15 be joined as series sets or individually re-
newed with great facility, the simple and
convenient member 14 being the only extra
or loose part.

20 All of the metal parts are preferably of
sherdized, or otherwise rust-proofed, malleable iron or steel, or they may be constructed of non-rusting material, such as copper, brass, etc. This insures effective co-operation between the members, prevents
25 deterioration and facilitates their assembly.

While I have shown and described a particular form of my invention, changes may be effected therein without departing from the spirit and scope thereof; as set forth in the appended claims.

I claim as my invention:

35 1. An insulator connector comprising a member extending transversely of the longitudinal axis of the insulator and having an eye portion at one end and a clevis portion at the other end for co-operation, respectively, with the clevis and eye portions of a similar member, said members also having tapered longitudinal openings therein laterally offset from said eye-and-clevis portions, a pin disposed between said tapered openings for co-operation with the eye-and-clevis portions, a U-shaped longitudinally halved member of rounded cross-sectional area having its ends in said tapered openings and wedges spreading the halves of each of said ends in said openings, the extreme ends of said halves being bent inwardly over the larger ends of the wedges.

40

45

50 2. An insulator connector comprising a member extending transversely of the longitudinal axis of the insulator and having longitudinally-extending transversely-apertured portions at each end for co-operation with the corresponding portions of a similar member, said member also having longitudinal openings therein laterally offset from said portions, a pin disposed between said openings for co-operation with the transversely apertured portions, a U-shaped longitudinally divided member of rounded cross-sectional area having its ends in said open-

ings, and a wedge spreading the divisions of each of said ends in said openings.

3. An insulator connector comprising a member extending transversely of the longitudinal axis of the insulator and having a single apertured portion at one end extending longitudinally of said axis and a pair of similar portions at the other end for co-operation, respectively, with the paired and single apertured portions of a similar member, and a single pin for co-operation with said apertured portions.

4. An insulator connector comprising a member extending transversely of the longitudinal axis of the insulator and having tapered longitudinal openings adjacent to the ends thereof, a U-shaped longitudinally halved member of rounded cross-sectional area having its ends in said tapered openings and a wedge spreading the halves of each of said ends in said openings.

5. A connector comprising a longitudinally-halved member having a rounded outer surface and flat inner surfaces for engagement with each other substantially throughout the length but separated adjacent to the ends thereof, and a terminal element co-operating with said separated portions to be held in operative relation thereto.

6. An insulator connector comprising a member having a tapered opening of rounded cross-sectional area therein and a longitudinally-divided member of rounded cross-sectional area having a portion in said opening, another portion of said longitudinally-divided member having flat engaging inner surfaces, and a wedge separating the divisions of said divided member in said opening. 100

7. A connector, comprising an elongated member having a rounded outer surface and longitudinally-halved separated end portions, and a terminal element co-operating with said separated end portions to be held in operative relation thereto.

8. A connector comprising a member having a tapered opening of rounded cross-sectional area therein and an elongated member of rounded cross-sectional area having a longitudinally-divided end portion in said opening, said end portion having separated plane adjacent surfaces, and a wedge separating the divisions of said divided portions in said opening having plane wedging surfaces between, and in engagement with, the plane surfaces of the elongated member. 110 115

In testimony whereof, I have hereunto, 120
subscribed my name this 3rd day of Sept.,
1919.

EDWARD E. ROSE.
